UNITED STATES PATENT OFFICE.

CARL SKOPAL, OF LETHBRIDGE, ALBERTA, CANADA.

GUN-SIGHT.

1,836,165.

Specification of Letters Patent.

Patented Apr. 6, 1920.

Application filed August 3, 1918. Serial No. 248,205.

To all whom it may concern:

Be it known that I, CARL SKOPAL, citizen of Bohemia, residing at Lethbridge, in the Province of Alberta and Dominion of Canada, have invented new and useful Improvements in Gun-Sights, described and claimed in my application filed August 3, 1918, Ser. No. 248,205.

The object of the invention is to provide a gun sight and particularly a fore sight for rifles, shot guns, machine guns and the like which shall not be open to the objection of becoming polished or discolored by reason of use or the heat of discharge of the piece, it being a well recognized fact that the most effective and satisfactory sight, for accuracy in firing, is of a dark color, preferably black and of a dull finish, so as to be nonreflective, and hence not such as to distract or distort the vision of the marksman.

In carrying out this object, the invention consists of the construction and combination hereinafter set forth, it being understood that changes in form and proportion may be resorted to without departing from the spirit of the disclosure.

In the drawing:

Figure 1 represents in side elevation a gun sight applied in the operative position to a barrel.

Fig. 2 is a rear view of the same as seen by the marksman.

Fig. 3 is a detail view of the sight detached.

Essentially, the invention consists in providing a fore sight of refractory material having a color, preferably black, which is not affected by heat or by frictional contact with other objects, and which is not susceptible of polish or of becoming shiny in use, and which therefore presents a uniform or "dead" sur-

face to the eye of the observer, to avoid that refraction which usually results in causing the marksman to over-fire the object. It has been found that dull ebony or metal which has been provided with a sufficiently durable surface coating of a dull black color is effective in this connection, and the blade 10 of the sight should be tapered upwardly and forwardly from the rear end to present a gradually reduced surface toward the apex 11. The blade may as in the ordinary practice be held in a base plate 12 fitted in the usual transverse undercut seat 13 in the barrel 14.

It has been found by actual test that the accuracy of aim is improved approximately 50% by providing a fore sight which presents a dull black surface to the eye of the marksman, as distinguished from one which has even a slight polish or reflective surface, for the reason that the effect of the reflection is to give the impression to the eye of the marksman that the apex of the foresight is lower than it actually is, and therefore induces him to elevate the gun more than is necessary to secure an accurate trajectory. These disadvantages are overcome by the complete elimination of reflection.

What is claimed is:

The combination with a gun barrel, of a base plate seated thereon adjacent the muzzle end of the barrel, and a fore sight consisting of a blade tapering upwardly and rearwardly from the front end to present a gradually reduced surface at the rear end, the blade being carried by the base plate and provided with a durable surface coating of a dull black color as and for the purpose herein specified.

In testimony whereof I affix my signature.
CARL SKOPAL.
